UNITED STATES PATENT OFFICE.

ANDERS ANDERSSON ROSENGREN, OF MALMO, SWEDEN.

MACHINE FOR SEALING BOTTLES.

1,081,931.

Specification of Letters Patent. Patented Dec. 16, 1913.

Application filed November 4, 1911. Serial No. 658,457.

To all whom it may concern:

Be it known that I, ANDERS ANDERSSON ROSENGREN, a subject of the King of Sweden, and resident of 86 Södra Förstadsgatan, 5 Malmö, in the Kingdom of Sweden, have invented certain new and useful Improvements in Machines for Sealing Bottles, of which the following is a specification, reference being made to the accompanying drawings.

10 The present invention relates to machines for applying sealing capsules to bottles and the like, and refers particularly to a type of such machine wherein jaws or similar members movable toward and from each other, 15 and which form part of the actuating means for a compressible rubber ring by which the caps are sealed on the bottles. The blanks of which the capsules are formed are obtained by punching them out from a band, a plate, 20 or the like. The capsules may be of a single thickness or of a plurality of thicknesses; in the latter case the capsule blanks are punched out from two or more bands superimposed so as to form one band.

25 The feature which chiefly characterizes the present invention is that the tool, by means of which the capsule blanks are punched out from the band, is operated as a consequence of the movement of the jaws 30 above referred to. The punching tool may preferably be provided with inclined surfaces, which coat with beveled portions or inclined surfaces arranged on the said jaws, the arrangement being such that, for instance, when the said jaws move toward each other, their inclined surfaces act upon the inclined surfaces of the punching tool in such a manner that the latter is moved and punches out a capsule blank.

40 Machines constructed in accordance with the present invention may be provided with a contrivance placed in front of the punching tool in the direction of movement of the blank band and intended for stamping or 45 otherwise producing in the band or those parts thereof, which are designed to form capsule blanks, desired information, such as designation of origin, description of contents, and a certain date, and, if desired, to 50 provide the band, or the capsule blanks, with rows of holes or other weakening lines along which the capsules are opened. The stamping and perforating contrivance may also

serve to feed forward the band toward the punching-out tool. 55

In the accompanying drawings which are illustrative of a machine embodying a preferred form of the invention. Figure 1 is a front elevational view of my invention; Fig. 2, is a sectional side elevation thereof; Fig. 3, is a plan view; Figs. 4 and 5 are sectional views at right angles to each other showing the upper part of the machine; Fig. 6 is an elevational view of a cam used for operating jaws which actuate 60 the punching tool; Fig. 7 is a bottom plan view of the punching tool; Fig. 8 is a vertical sectional view of mechanism for stamping and perforating strips or bands; and Fig. 9 is a fragment of a band out of which 65 capsules are punched. Fig. 10 is a horizontal sectional view of the sealing head of the machine; and Fig. 11 is a view similar to Fig. 5 but showing the parts in a different 70 position.

75 The frame of the machine consists of a base 1, a vertical standard 2, an arm 3 projecting from the upper part of the standard and a head 4, which is carried by the free end of the arm 3. The standard 2 is furnished with an opening in which there is a vertically movable block 5, provided with side pieces, which are located in vertical grooves 7, arranged in the standard 2, the walls of said grooves 7 serving as guides 80 for the side pieces of the block 5 during its movement in a vertical direction. In the lower part of the block 5 is fixed a non-rotatable screw spindle 8, which passes through the upper part of the base 1, and 85 on which screw spindle 8 is fitted a hand wheel 9, by the revolution of which the block 5 can be raised or lowered. In the block 5 is mounted a non-rotating shaft 10, which carries a pulley 11, an idler, and a toothed 90 wheel 13, which latter is firmly attached to the pulley. Moreover, in the block is journaled a rotatable shaft 14, at one end of which is fixed a toothed wheel 15, which is in engagement with the toothed wheel 13, 100 while at the other end of the shaft 14 is fixed a cam 16, against which rests a roller 17, mounted on the under side of a support 18 for the bottles to which the capsules are to be applied. From the support 18 project arms 19, at their free ends furnished 105

with sleeves 20, which surround rods 21 attached to the standard 2 and the arm 3, said rods 21 serving as guides for the support 18, when the latter moves in a vertical direction, which movement is caused by the cam 16. In the support 18 is journaled a screw spindle 22, which passes through a slide 23 movable horizontally in the support, the slide 23 being provided on its upper side with a shield 24, against which the bottles are placed when they are put on the support for sealing. As the shield is thus adjustable, the bottles, no matter what their diameter is, can always be properly positioned on the support, *i. e.* so that the axis of each bottle coincides with the axis of the sealing tool, with which latter axis the axis of the punching tool coincides. The machine is adjusted at different times with regard to the height of the bottles, by raising or lowering the block 5 with the aid of the hand wheel 9, so that the heads of the bottles will be at the proper height, when the sealing takes place.

In the machine frame is journaled a vertical shaft 25, surrounded by a worm wheel 26, which is joined to the shaft 25 in such a manner that it can be displaced along the shaft, but not turned on the same by means of a groove arranged in the shaft and a pin fixed to the worm wheel and entering the groove. The worm wheel 26, which is placed between ears or the like on the block 5, so that it is displaced on the shaft 25, when the block is raised or lowered, meshes with a worm wheel 27, fixed to the shaft 14 carrying the toothed wheel 15, so that, when the pulley 11 is rotated, the shaft 25 rotates with it, no matter what the height of the block 5 and the support 18 is.

At the upper end of the shaft 25 is attached gear wheel 28, which meshes with a gear 29, this gear being more fully hereinafter described. In the vicinity of the gear wheel 28 the shaft 25 carries a worm wheel 30.

Mounted in a cavity in the head 4 is a pair of jaws, each composed of a lower plate 31 and an upper plate 32. The jaws which are movable toward and from each other, are of rectangular form, and the upper and lower plates of each jaw are integral. The upper plates 32 are provided with beveled or inclined portions 33 designed to engage correspondingly inclined portions 33^a formed on a compressor member 34, and the lower plates are provided with beveled or inclined portions 44 designed to engage correspondingly inclined portions 44^a on the punching tube 40, as more fully hereinafter explained. The jaws form part of the means for actuating the compressor 34 and the punching tube 40. The compressor 34 is reciprocable in and guided by a socket 35 positioned between the upper and lower jaw

members 31 and 32, and between the under face of the compressor 34 and the upper face of a shoulder formed at the bottom of the socket 35 is arranged a rubber ring 36, rectangular in cross section.

When the jaws move toward each other, the compressor—in consequence of the action of the inclined surfaces 33 on the corresponding surfaces 33^a on the compressor—is driven downward, whereby it compresses the rubber ring 36, and causes the sealing of a bottle.

During the sealing operation the head of the bottle must be at a certain height so that the cap upon the bottle neck will be located within the rubber ring 36. For this purpose the circumference of the cam 16 between the points *a* and *b* is bent along a constant radius, one end of which coincides with the axis of the shaft 14.

As has been mentioned above, the capsules in the present case may comprise several thicknesses, each capsule consisting of an outer metallic part, made, for instance, of aluminium, and an inner part, consisting of parchment paper or the like. A practically perfect seal is thus obtained, which prevents the escape of carbonic acid from the bottles, when their contents consist of aerated water or beer. The material for forming the capsules is obtained from two spools or reels 37 and 38, which are carried by the upper part of the machine frame; the bands which are unrolled from these spools are superimposed to form a single band 39, out of which the capsule blanks are punched.

The punching of the capsule blanks from the band 39 is effected with the aid of a punching tube 40, the lower part of which forms a cutting or punching edge. The punching tube is partly within and partly above a part 41, which is fixed in the frame head 4 and serves as a matrix for the punching tube. Both the head 4 and the matrix 41 are provided with a groove 42, which is intended for the band 39, the dimensions of the groove corresponding to the breadth and thickness of the band. The punching tube 40 at its upper part is connected to or formed integrally with, a plate 43, placed in the frame head 4, by which it is guided. Between the plate 43 and the matrix 41 are placed one or more springs 43^a or any other elastic body or bodies, serving to return the punching tube, after the punching operation.

In order to produce the downward movement of the punch the lower plates 31 of the jaws 31—32 are provided with downwardly inclined surfaces 44 and the plate 43 of the punch 40 is provided with a coacting inclined surface 44^a.

When the jaws 31 and 32 move toward each other, and the surfaces 44 act on the surfaces 44^a, the punching tube 40 will be

caused to move downward, so that its edge is driven through the band 39, out of which a capsule blank is thus punched. The punched-out capsule blank falls onto a shoulder 45, situated immediately below the matrix 41, and rests on it, till it comes into contact with a bottle head which is moving upward. The shoulder 45 is formed on a plate 45^a which constitutes the lower part of the head 4, and which plate supports the matrix 41.

The moving of the jaws 31 and 32 toward and from each other is effected by the following mechanism. The gear 29, which is rotatably mounted on a shaft 46 fixed in the upper part of the frame head 4, is provided on its lower side (Fig. 6) with a continuous cam groove 47, into which enter pins 48^a, fixed each on one of the sliding jaws. The said pins 48^a which pass up through notches 49 into the frame head 4, are provided with antifriction rollers 48, against which the walls of the groove act. The groove comprises five pairs of similar but oppositely located elements or parts. When the groove parts *c*—*d*—during the rotation of the gear 29 in the direction of the arrow (Fig. 6)—engage the pins 48, the jaws 31 and 32 are held in their extreme positions; and while so held the reciprocating movement of the bottle support 18—takes place and the sealed bottle is replaced by one which is to be sealed. When thereafter the groove parts *d*—*e* engage the pins 48, the jaws, in consequence of the pressure which the outer walls of the said groove parts exert on the pins are moved somewhat inward, whereby the punching tube 40, in consequence of the action of the surfaces 44 on the surfaces 44^a is driven downward to the position shown in Figs 4 and 5, so that its edge pierces the band 39, punching out a capsule blank which falls on the shoulder 45; at the same time the bottle which is to be sealed continues to move upward. The groove parts *e*—*f* then engage the pins 48, and the jaws are held stationary in the position indicated in Figs. 4 and 5 while the bottle still continues to move upward, carrying with it the capsule blank resting on the bottle head, the outer ring-shaped part of the blank being wrapped by the punching tube 40 around the bottle head. At the end of this movement the bottle head attains its highest position between the jaws, in which position it remains for a moment in consequence of the portion *a*—*b* on the cam passing under the roller 17. During this time the groove parts *f*—*g* engage the pins 48, which are acted upon by the outer walls of the groove parts in such a manner that the jaws are pressed farther inward; during this movement of the jaws the surfaces 33 on the jaws act on the surfaces 33^a on the compressor 34, so that the sealing

of the bottle takes place. Thereupon the groove parts *g*—*c* engage the pins 48, which are acted upon by the inner walls of these groove parts in such a manner that the jaws are moved out to their extreme positions, and the above mentioned movements are repeated.

On account of the diametrical arrangement of the parts of the groove 47, the gear 29 need only turn half a revolution, while the gear wheel 28 which drives the disk and which rotates with the same speed as the cam shaft 14, turns a whole revolution.

As will be seen from Fig. 7, which shows the punching tool seen from below, there is on the outer side of the punching tube 40 a projection 40^a, which serves at the punching out of a capsule blank to produce a tongue intended to be acted upon for tearing off the capsules in opening the bottles.

The shaft 46 is hollow and surrounds in its longitudinal direction an axially movable spindle 50, the upper free end of which carries a preferably adjustable weight 51, while to its lower end is fixed a piston or plate 52, which rests against a capsule blank when the latter, resting on a bottle head, moves upward toward the jaws. In order that the capsule blank may be kept centered from the very outset of its movement upward from the shoulder 45, the piston or plate 52 should be situated immediately above the capsule blank resting on the shoulder. However, in order that the lower part of the spindle 50 or the plate 52 may not be in the way of the band 39 when this is being fed forward, the following arrangement has been adopted. The spindle 50 is provided with a ridge 50^a which passes through a corresponding groove in the fixed shaft 46, so that the spindle cannot revolve. A sleeve 50^b firmly connected with the spindle 50, is on its under side provided with projections 50^c, for which corresponding notches are made in the nave of the disk 29, which nave is prolonged upward. When the bottle head moves upward toward the jaws, whereby the capsule blank is jammed between the bottle head and the plate 52, no feeding forward of the band 39 takes place. When the bottle head, after the sealing has taken place, moves downward, the spindle 50 follows with it, until the projections 50^c come to rest on the plane upper side of the nave of the gear 29. Thereby the spindle, and the plate 52, are kept at such a height as not to hinder the feeding forward of the band which now takes place. During the continued rotation of the gear 29 the projections 50^c move down into the corresponding notches in the nave, so that the plate 52 will engage a capsule blank resting on the shoulder 45.

The weight 51 can obviously be replaced by a spring or the like.

4
Before the capsule blanks are punched out of the bands 39, the latter passes through a contrivance in which the parts of the band which will subsequently form the capsule blanks are both stamped or otherwise furnished with required information, and perforated, or otherwise provided with a weakening line along which the capsules are opened. In the machine shown in the drawings, the contrivance in question consists of rollers (Figs. 4 and 8), the lower one of which, the so-called "male roller" 53, with the aid of a worm-wheel fixed on its shaft 54, is driven by the worm wheel 30 on the shaft 25, while the upper roller, the so-called "female roller" 56, by means of a toothed wheel gearing receives its movement from the male roller. Carried on the periphery of the roller 53 is a male die member 57 adapted to coöperate with a female die member 58 secured to a flexible plate 59 which, in turn, is secured to the periphery of the roller 56. It will be understood that both the male and female die members are removably secured to the rollers which carry them. The male die 57 is also provided with a number of projections, serving to punch out rows of holes in the band 39; each of these rows forms in a finished capsule an opening line, which extends along half the bottle head (see Fig. 9.) When the bottle has been opened by removal of the tongue from the capsule, the remaining portion of the latter may be used as a temporary cover for the bottle mouth.

The shaft 60 of the female roller 56 has its ends mounted eccentrically with reference to the central part upon which the roller 56 is mounted, in consequence of which the female roller can, in order to insert the band 39 between the said roller and the male roller, be separated from the latter roller. The turning of the shaft 60, whereby also the feeding forward of the band can be interrupted, is effected with the aid of a crank 61 fixed on one end of the shaft.

It will be understood that the band 39 is fed to the punching tool 40 by means of the rollers 53 and 56 which are properly dimensioned to effect the desired amount of feed.

In order that the band 39 may stop, as soon as its feeding forward ceases, it is acted upon by a brake device, preferably in the form of a roller 63 fitted on elastic arms 62, which roller 63 presses the band against a bridge 64, extending from the rollers 37, 38 to the rollers 53, 56.

From the rollers 53 and 56 the band 39 passes to the punching mechanism through a channel shaped guide 65. In order that that part of the band 39, out of which the capsule blanks has been punched, may not project out from the frame head 4 and be in the way, it can be cut off bit by bit. For this purpose there are placed at the front side of

the frame head, immediately in front of the mouth of the groove 42, two shear blades 66, which are at one end pivotally fixed to the frame head by means of a pin 67, and are at their other end provided each with an oblique groove 68. These grooves 69 are traversed by a pin, fixed on an arm 69, which extends from one of the jaws, in consequence of which, when the jaws move toward and from each other, the shear shanks also move toward and from each other, thereby cutting off bit by bit of the punched part of the band 39. The bits thus cut off can be carried away in a suitable manner.

The machine above described, the operation of which will be clearly understood from the foregoing part of the specification, is mainly intended for being driven by motor, though it can also be arranged to be driven by hand. In any case the gearings and the like in the machine must be such that its different mechanisms work in time with each other.

Having now described my invention, what I claim as new and desire to secure by Letters Patent is:

1. A machine for sealing bottles, embodying therein a reciprocable tool for punching capsule blanks from a continuous strip of material, said tool having inclined surfaces thereon, jaws movable toward and from each other in a direction toward and from the axis of said tool, said jaws having inclined surfaces, in the paths of which the inclined surfaces of the tool are situated, and means for forcing said jaws toward each other whereby the inclined surfaces thereof coact with the inclined surfaces of the tool to actuate the latter.

2. In a machine for applying capsules to bottles and the like, the combination of a tool for punching out capsule blanks from a strip, movable jaws, inclined surfaces on said jaws, inclined surfaces on the punching tool, the latter surfaces being acted upon by the inclined surfaces on the jaws in order to cause the tool to punch out a capsule blank, a rubber ring, adapted to squeeze the capsule blanks around the necks of the bottles, a compressor for compressing said rubber ring, means whereby said punching tool and compressor are maintained in alinement and inclined surfaces on the compressor, which latter surfaces are acted upon by the inclined surfaces on the jaws to cause the compressor to compress the rubber ring for the sealing of a bottle.

3. In a machine for applying capsules to bottles and the like, the combination of a reciprocable tool for punching out capsule blanks from a strip, jaws movable toward and from each other in a direction toward and from the axis of said tool, inclined surfaces on said jaws, inclined surfaces on the punching tool, the latter surfaces being

acted upon by the inclined surfaces on the jaws to cause the tool to punch out a capsule blank, a rotating disk having a groove therein, and means projecting from the jaws 5 into said groove and by which said jaws are moved toward and from each other during rotation of said disks.

4. In a machine for applying capsules to bottles and the like, the combination of a 10 tool for punching out capsule blanks from a strip, movable jaws, a plurality of inclined surfaces on each of said jaws, inclined surfaces on the punching tool, the latter surfaces being acted upon by one of the inclined 15 surfaces on each of the jaws to cause the tool to punch out a capsule blank, a rubber ring, adapted to squeeze the capsule blanks around the necks of the vessels, a compressor for compressing the rubber ring for said operation, inclined surfaces on the compressor, which latter surfaces are acted upon 20 by another of the inclined surfaces on each of the jaws to cause the compressor to compress the rubber ring for the sealing of a 25 bottle, a rotating disk, a groove in said disk, and means extending from the jaws and entering into said groove for joining said disk to said jaws.

5. In a machine for applying capsules to 30 bottles and the like, the combination of a tool for punching out capsule blanks from a strip, means for feeding said strip to said tool, movable jaws, inclined surfaces on said jaws, inclined surfaces on the punching tool, 35 the latter surfaces being acted upon by the inclined surfaces on the jaws to cause the tool to punch out a capsule blank, and a device for successively cutting pieces off from that part of the strip out of which capsule 40 blanks have been punched.

6. In a machine for applying capsules to bottles and the like, the combination of a 45 reciprocable tool for punching out capsule blanks from a strip, jaws movable toward and from each other in a direction toward 50 and from the axis of the tool, inclined surfaces on said jaws, inclined surfaces on the punching tool, the latter surfaces being acted upon by the inclined surfaces on the jaws to cause the tool to punch out a capsule blank, and a pair of rollers for feeding the capsule blank strip to the punching device.

7. In a machine for applying capsules to 55 bottles and the like, the combination of a tool for punching out capsule blanks from a strip, means for feeding said strip to said tool, movable jaws, inclined surfaces on said jaws, inclined surfaces on the punching tool, the latter surfaces being acted upon by the

inclined surfaces on the jaws to cause the 60 tool to punch out a capsule blank, a roller provided with a male die member for stamping indications in the capsule blank strip, and a roller provided with a female die member coacting with said male die member. 65

8. In a machine for applying capsules to bottles and the like, the combination of a 70 tool for punching out capsule blanks from a strip, means for feeding said strip to said tool, movable jaws, inclined surfaces on said jaws, inclined surfaces on the punching tool, the latter surfaces being acted upon by the inclined surfaces on the jaws to cause the tool to punch out a capsule blank, a roller provided with a male die member for producing 75 in the capsule blank strip weakening lines, and a roller provided with a female die member coacting with said male die member.

9. In a machine for applying capsules to 80 bottles and the like, the combination of a tool for punching out capsule blanks from a strip, movable jaws, inclined surfaces on said jaws, inclined surfaces on the punching tool, the latter surfaces being acted upon by 85 the inclined surfaces on the jaws in order to cause the tool to punch out a capsule blank, a support on which the bottles to be provided with capsules rest and which is movable toward and from the punching tool, and a 90 shield against which the vessels are placed and which is adjustable on the support to hold the vessels in proper alinement with the punching tool.

10. In a machine for applying capsules to 95 bottles and the like, the combination of a tool for punching out capsule blanks from a strip, movable jaws, inclined surfaces on said jaws, inclined surfaces on the punching tool, the latter surfaces being acted upon by 100 the inclined surfaces on the jaws to cause the tool to punch out a capsule blank, a support on which the bottles to be provided with capsules rest and which is movable toward and from the punching tool, a shield 105 against which the bottles are placed and which is adjustable on the support to hold the bottles in proper alinement with the punching tool, and a cam moving the support toward and from the punching tool and 110 arranged to hold the bottle at rest during the sealing operation.

In witness whereof I have hereunto set my hand in presence of two witnesses.

ANDERS ANDERSSON ROSENGREN.
